[57] **CLAIM**

The ornamental design of a bracket component for forming a staircase, substantially as shown and described.

DESCRIPTION

FIG. 1 is a front perspective view from above and one side of one embodiment of a bracket component for forming a staircase;

FIG. 2 is a side elevational view of the component of FIG. 1;

FIG. 3 is a rear elevational view of component of FIG. 1;

FIG. 4 is a front perspective view from above and one side of a second embodiment of the component;

FIG. 5 is a side elevational view of the component of FIG. 4; and

FIG. 6 is a rear elevational view of the component of FIG. 4.

Fig. 1.

Fig. 2.

Fig. 3.

Fig.4.

Fig.5.
